UNITED STATES PATENT OFFICE.

FLORIAN ANDREW KOMOROWSKI, OF WILMINGTON, DELAWARE.

RADIO LOUD SPEAKER.

Application filed November 8, 1924. Serial No. 748,679.

To all whom it may concern:

Be it known that I, FLORIAN A. KOMOROWSKI, a citizen of the United States, residing at Wilmington, in the county of New Castle and State of Delaware, have invented new and useful Improvements in Radio Loud Speakers, of which the following is a specification.

This invention relates to radio apparatus particularly to amplifying devices commonly known as loud speakers, and has for its object the provision of a novel device of this character designed either for suspension from a ceiling or other support or constructed so as to be set upon a table or the like, the device being formed for use in connection with an ordinary unit such as a telephone unit of the ordinary variety or of the so-called loud speaking variety.

20 The essential object of the invention is the provision of a loud speaker which involves the use of a bowl shaped reflector against which the sound waves are concentrated by means of a conduit member at one end of which is located the telephone unit, the bowl shaped member acting to magnify the sound and throw it in the desired direction.

Another object is the provision of a device of this character which is so constructed and arranged that it may be used in either form, that is, the suspended form or the table form, simple attachments being provided whereby the conversion may be made from one to the other.

35 Another object is the provision of a device of this character which may be made extremely ornamental in appearance so as to be very attractive instead of unsightly as is the case with the ordinary type of loud speaker embodying a horn.

Still another object is the provision of a device of this character which on account of its peculiar construction will be more advantageous than the ordinary horn type inasmuch as the tone will be clearer and free from the distortion which so often results from the use of the well-known type.

An additional object is the provision of a device of this character which will be simple and inexpensive to manufacture, easy to in-

stall, positive in action, efficient and durable in use and a general improvement in the art.

With the above and other objects and advantages in view, the invention consists in the details of construction to be hereinafter more fully described and claimed, and illustrated in the accompanying drawings in which:

Figure 1 is a side elevation of the device showing the table form thereof, the bowl member being in section, 60

Figure 2 is a vertical section on the line 2-2 of Figure 1,

Figure 3 is a detail section on the line 3-3 of Figure 1, 65

Figure 4 is a detail section showing the connection of the standard with the base,

Figure 5 is a perspective view of the device showing the suspension form thereof, and 70

Figure 6 is a longitudinal section through this form.

Referring more particularly to the drawings, the numeral 10 designates an elongated tubular conduit which has one end slightly constricted as shown at 11 for suitable engagement with a phone or loud speaker unit indicated at 12. The details of this unit are not disclosed as they form no part of the present invention and as these devices are on the market and well known. It suffices to say, that this unit is equipped with wires 13 which are adapted to be connected with the output from any radio set whereby to operate the unit. The other end of this member 10 is outwardly flared as indicated at 14, and carries a bell-like member 15 of suitable material which is here represented as secured in place by set screws 16 or the like. This member 15 is substantially the same as a globe used in connection with electric lights and in fact such a globe may actually be used if preferred. 85

Slidably adjustably mounted upon the tubular conduit member 10 is a collar 17 held in adjusted position by means of a set screw 18 or the like and formed at one side with a threaded socket 19 for a purpose to be described. The numeral 20 designates a bowl shaped reflector or deflector which 90

2
may be of metal, glass, china, porcelain or any other suitable material and of any desired size. This bowl shaped member may be ornamented on one or both sides, as preferred, in order that the entire device will have a most pleasing appearance. Secured to the edge portions of the reflector or bowl 20 are rods or other brace elements 21 which converge and which are connected with the 10 collar 17 as shown. Obviously, by loosening the set screw 18, the collar 17 and the bowl member 20 may be adjusted with respect to the member 15 so as to vary the space between the outlet or open end of the 15 member 15 and the center of the bowl. This adjustment is necessary in order to secure the best results and to project the sound most efficiently in the desired direction so that proper amplification will be had while 20 the quality remains clear, loud and sweet.

As shown in Figures 5 and 6, the device is well adapted for suspension from a ceiling or other overhead support and in carrying out this feature, I provide an attaching 25 plate member 22 which may be screwed, nailed or otherwise fastened to a ceiling or other support and which is provided with a suspension element 23 from which depend chains or other flexible members 24 connected at 25 with the bowl or reflector 20.

The device is equally capable of use mounted upon a table, shelf or other support, and for this reason I make use of a standard or post 26 having a threaded end 30 adapted to be screwed into the threaded socket 19 which forms a part of the collar 17. At its lower end, the post or standard 26 has a threaded extension 27 which is screwed into an upstanding ferrule 28 mounted at the center of a suitable base 29 which is preferably equipped with rubber feet 30 to avoid marring the top of the table or the like. When the device is used in the horizontal or table position as shown in 45 Figure 3, it is necessary to provide a counterbalancing weight 31 to compensate for and balance the weight of the bowl like reflector 20. This counterbalancing weight 31 is shown as equipped with a suspension 50 ring 32 or the like engaged upon the constricted end portion 11 of the member 10 as clearly shown in Figure 1.

In the use of the device it is quite apparent that the sound waves will travel from 55 the unit 12 through the tubular conduit member 10 and will be concentrated by the member 15 onto the center of the bowl or reflector 20, from which the sound waves will be reflected back in a magnified form 60 so as to be clearly audible all over a room or other place. In actual practice I have discovered that the provision of this bowl device gives the proper amplification without in any way causing any distortion of 65 the sound and in this way the device acts

far more efficiently and satisfactorily than the well known type of loud speaker employing a horn. Owing to the fewness of the parts and the adjustable features it is quite evident that the device is bound to 70 act efficiently even under the most adverse circumstances so that good results will be obtained at all times.

While I have shown and described the preferred embodiment of the invention, it 75 should be understood that I reserve the right to make such changes in the form, construction and arrangement of parts as will not depart from the spirit of the invention or the scope of the subjoined claims.

Having thus described the invention, I claim:

1. In a device of the character described, an elongated tubular conduit member, one end of the member being adapted for connection with a loud speaker unit, a bell member detachably connected with the other end of said member, a bowl like reflector supported upon the member, and means for adjusting the reflector whereby to vary the 80 distance between it and said bell member.

2. In a device of the character described, an elongated tubular conduit member having one end formed for connection with a loud speaker unit, a bell member on the 85 other end of said tubular member, a collar slidably, adjustably mounted along said tubular member, a bowl like reflector spaced from the end of said bell member, and a plurality of supporting elements carried by 90 said collar and connected with said reflector.

3. In a device of the character described, an elongated tubular conduit member, one end of the member being adapted for connection with a loud speaker unit, a bell 105 member detachably connected with the other end of said member, a bowl like reflector supported upon the member, and means for adjusting the reflector whereby to vary the distance between it and said bell member, 110 said bowl being adapted for support selectively in horizontal or vertical positions.

4. In a device of the character described, an elongated tubular conduit member having one end formed for connection with a 115 loud speaker unit, a bell member on the other end of said tubular member, a collar slidably, adjustably mounted along said tubular member, a bowl like reflector spaced from the end of said bell member, and a 120 plurality of supporting elements carried by said collar and connected with said reflector, and a supporting stand detachably connected with said collar.

5. In a device of the character described, an elongated tubular conduit member having one end formed for connection with a 125 loud speaker unit, a bell member on the other end of said tubular member, a collar slidably, adjustably mounted along said 130

tubular member, a bowl like reflector spaced from the end of said bell member, a plurality of supporting elements carried by said collar and connected with said reflector, a supporting stand detachably connected with said collar, and a counterbalancing weight detachably engageable upon the first named

end of said tubular member for counter-balancing the weight of the reflector when said tubular member is arranged in horizontal position.

In testimony whereof I affix my signature.

FLORIAN ANDREW KOMOROWSKI.
